MEDICINE CABINET OR SIMILAR ARTICLE

Stephen W. Gehrs, 7502 Baird St., Encino, Calif.

Filed Aug. 11, 1960, Ser. No. 61,695

Term of patent 14 years

(Cl. D4—3)

FIGURE 1 is a front perspective view taken from the top and one end of a medicine cabinet or similar article, showing my new design;

I claim:

The ornamental design for a medicine cabinet or similar article, substantially as shown.
